Inventor

A. Kimbel

United States Patent Office.

ANTON KIMBEL, OF NEW YORK, N. Y.

Design No. 4,634, dated February 7, 1871.

DESIGN FOR A CHAIR.

The Schedule referred to in these Letters Patent and making part of the same.

To all whom it may concern:

Be it known that I, ANTON KIMBEL, of New York, in the State of New York, have invented and produced a new and original Design for Chairs, of which the following is a specification.

The nature of my design is fully represented in the accompanying drawings, to which reference is made, where—

Figure I represents a perspective front view of my improved chair; and

Figure II shows a side elevation.

The back of the chair A, forming, likewise, the back legs, is slightly curved outward at top and bottom.

Near the seat B a piece of wood, C, is attached to the back pieces A, running forward and diagonally

downward, slightly bent on its forward end, and forming the front legs of the chair.

The seat B is attached to the back pieces A, close to the connecting-place of the piece C with the back-piece A, and is supported near the front by the support D resting upon the piece C.

These pieces C, or front legs, are connected together by the bars E, and the back-pieces A are connected together near the top by the bars F.

What I claim as my invention, and desire to secure by Letters Patent, is—

The design for a chair, as described and shown.

Witnesses:

ANTON KIMBEL.

HENRY E. ROEDER,
JOHN CHRISTIAN.
